UNITED STATES PATENT OFFICE.

SEBASTIANO FASCI, OF SOUTH WEYMOUTH, MASSACHUSETTS.

AUTOMOBILE SIGNAL.

Application filed December 1, 1921. Serial No. 519,049.

To all whom it may concern:

Be it known that I, SEBASTIANO FASCI, a citizen of the United States, and a resident of South Weymouth, in the county of Norfolk and State of Massachusetts, have invented a new and useful Improvement in Automobile Signals, of which the following is a specification.

My invention relates to automobile signals and its object is to provide a device for signalling to following vehicles that the operation of a car is about to be changed, as for example, that it is about to turn to the right or the left with the usual preliminary slowing down, or that it is about to stop or back or to slow down without turning, and to signal such information without the use of multi-colored lights or words or letters which are visible only for relatively short distances, and to signal to persons in front of the car that the car is about to turn to the right or to the left.

With these objects in view my invention comprises a rear signal in the form of a rotatable disc with distinctive markings such for example as relatively large openings, each surrounded by a band of color contrasting with the color of the disc and means operable by the driver for rapidly rotating said disc in one direction, a spring or other resili- 25 ent means serving to bring the disc to its normal position by a rapid rotary movement, as set forth in my application Serial No. 499,141, filed September 8, 1921, together with front signals consisting of semaphores arranged in proximity to the head lamps whereby to indicate the direction in which the car is to be turned, and a single apparatus for moving one semaphore across the 30 face of its adjacent lamp without actuating the other, said means being so arranged that its operation for actuating either semaphore will impart a rapid rotary movement in one direction to the rearwardly located disc, a spiral spring restoring said disc to normal 35 position by a rapid rotary movement.

In the drawings which accompany and form a part of this specification:—

Figure 1 is a diagram illustrating the principle of my invention;

Fig. 2 is a front view of an automobile provided with my improved front signal;

Fig. 3 is a front elevation of the rear signal;

Fig. 4 is a front elevation on an enlarged scale of one of the front signals;

Fig. 5 is a vertical section taken on the line 5—5 of Fig. 4.

In the particular drawings selected for more fully disclosing my invention and which it will be understood are merely illustrative and not restrictive, inasmuch as my invention may be embodied in a variety of apparatus without departing from the spirit thereof, 10 represents a housing secured in any suitable manner to the rear end of an automobile and enclosing the tail lamp 11. Located within said housing and covering the front thereof is a disc 12 of metal or other suitable material, said disc being fixedly secured to the shaft 13 having its bearings in the rear wall of said housing and in the collar 14 secured to said housing by the rods 15.

By means of the spiral spring 16 having its ends attached to said shaft and to the rear wall of the casing, respectively, a finger 17 on said disc is maintained normally against the stop member 18 fixed to the inner surface of said housing, said spring being under a certain amount of tension when said finger is in engagement with said stop member, whereby said disc is maintained in its normal position with the opening 19 thereof in front of the tail light 11. The disc is provided with distinctive markings shown in the present instance as a plurality of holes 19, 20, 21, 22, each surrounded by a band of color 23, which contrasts with the color of the disc, although it will be obvious that various other forms of distinctive markings may be employed.

Passing over a pulley 24 rigidly secured to the shaft 13 is a cord 25 suitably guided to a point in proximity to the driver, so that by pulling the cord forward, a rigid rotary movement is imparted to the disc 12 and by releasing said cord the spring 16 will restore the disc to its normal position by a rapid rotary movement, thereby causing the disc 100 to whirl rapidly and thus intermittently cutting off and flashing the light of the tail lamp when the latter is employed. For daylight signaling when the tail lamp is not lighted, the rapid rotation of the disc provided as aforesaid with distinctive markings is visible for much greater distances than pointers and characters ordinarily employed for automobile signalling.

Various means may be employed for operating the rear signal by means of the cord 25, and as hereinafter more fully set forth,

I prefer to use a single apparatus whereby said rear signal is actuated simultaneously with either one of the forward signals, consisting in the present instance of semaphores 5 26, 26', located in proximity to the head lamps 27, 27', respectively. Each semaphore preferably of red glass is carried by an arm 28 rigidly secured to the rock shaft 29 on which is mounted a pulley 30 around which 10 passes a cord 31, one end of such cord being secured to said pulley. By means of the helical spring 32 having its ends secured to one of the walls of the casing 33 and the rock shaft 29, respectively, the semaphore is maintained 15 in a vertical position with the finger 34 projecting from said rock shaft in engagement with the stop member 35 attached to the side wall of said casing. It will be obvious that as the cord 31 is unwound from 20 the pulley 30, the semaphore may be rotated through an arc of about ninety degrees across the face of its adjacent headlight as indicated in dotted lines in Fig. 4, and thereby signal the information that the car is about 25 to make a turn in the direction corresponding with the position on the car of the semaphore which has been moved to a horizontal position.

One of the numerous means whereby one 30 of the semaphores may be actuated without moving the other is indicated diagrammatically in Fig. 1 wherein 36 indicates a forked lever secured for oscillation about the steering post 37, the cords 31, 31' being attached 35 to the ends of the fork. It will be obvious that as the handle 38 of said lever is turned slightly about the steering post in one direction, the semaphore 26 will be moved across the face of its adjacent headlight to 40 indicate that the car is to make a turn to the right, while the semaphore 26' will remain stationary, and that when it is moved about the steering post in the opposite direction, the cord 31' will be drawn toward the rear 45 and the semaphore 26' moved to a horizontal position to indicate that the car is to turn to the left.

Inasmuch as a turn in either direction is preceded by a reduction in speed, it is desirable 50 to signal to the following cars the fact that the automobile is about to change its operation, and one of the various ways in which this result may be effected is indicated diagrammatically in Fig. 1, viz., the cords 55 39, 39' are secured to the cord 25 and to the respective forks of the lever 36, so that an oscillation of the handle 38 in either direction will draw the cord 25 forward and whirl the disc 12. It will be noted that it is not 60 necessary that the following cars should know in which direction the signalling car is about to turn or in fact that its change of operation involves a turn. The driver of the car following on observing the whirling of 65 the disc 12 is at once informed that the sig-

nalling car is about to change its operation and accordingly he reduces the speed of his own car in preparation for such change whether the same is to be a stop or a turn or merely a slowing down. If desired a knob 70 40 may be fixed on the cord 25 in proximity to the driver to provide for the independent oscillation of the rear signal, as when the car is about to reduce its speed without turning, or to stop or to back. 75

In order to ensure the reception by the following cars of the signals transmitted by the disc 12 when the car is about to make a turn, the driver preferably will oscillate the handle 38 several times about the steering post 80 37 in such manner as to move only one of the semaphores from vertical to horizontal positions several times, that is, by moving the handle 38 from its normal position to the right and back to normal several times, or 85 to the left and back to normal several times, finally maintaining it to the right or left of normal until his signal has been acknowledged by the traffic officer. In this manner the disc 12 will be given a number of rapid oscillations in both directions and the cars in the rear will have ample opportunity to 90 reduce their speeds.

It will be understood of course that the unitary means for moving either semaphore 95 without actuating the other and operating the rear signal for each movement of either semaphore, may be located on the dash board or in any other position which is convenient to the driver, and that it may be operated by a treadle. 100

Having thus particularly described an illustrative embodiment of my invention without limiting the same thereto, what I claim and desire to secure by Letters Patent is:—

1. An automobile signal comprising in combination, head lamps located on either side of the car, semaphores arranged in proximity to said lamps, respectively, and a unitary means for moving either semaphore across the face of its adjacent lamp without actuating the other semaphore. 110

2. An automobile signal comprising in combination, head lamps located on either side of the car, semaphores arranged in proximity to said lamps, respectively, a unitary means for moving either semaphore across the face of its adjacent lamp without actuating the other semaphore, a rotatable disc having distinctive markings located at the rear of the car, a connection between said disc and said means whereby the actuation of said means for operating either one of said semaphores will impart to said disc 120 a rapid rotary movement in one direction and resilient means for imparting to said disc a rapid rotary movement in the opposite direction. 125

3. An automobile signal comprising in 130

combination, apparatus located on the forward portion of the car for indicating the direction in which said car is about to turn, apparatus located on the rearward end of the car for indicating that said car is about to change its operation, a unitary means for actuating the forward and rearward appa-

ratus simultaneously, and means for actuating said rearward apparatus independently of said forward apparatus. 10

In testimony whereof, I have hereunto subscribed my name this 28th day of November, 1921.

SEBASTIANO FASCI.
